(57) **CLAIM**

The ornamental design for a combined refuse and recycle bin organizer, as shown and described.

DESCRIPTION

FIG. 1 is a perspective environmental front side view of the combined refuse and recycle bin organizer thereof;

FIG. 2 is a perspective front side view thereof;

FIG. 3 is a front side view thereof;

FIG. 4 is a back side view thereof;

FIG. 5 is a left side view thereof;

FIG. 6 is a right side view thereof;

FIG. 7 is a top plan view thereof; and,

FIG. 8 is a bottom plan view thereof.

The broken line showing of chains and wheels in FIG. 1 is included for the purpose of illustrating environment and forms no part of the claimed design.
